UNITED STATES PATENT OFFICE.

EDWARD P. COLE, OF CHICAGO, ILLINOIS, ASSIGNOR TO COLE MANUFACTURING COMPANY, OF CHICAGO, ILLINOIS, A CORPORATION.

DESIGN FOR A RANGE-TOP.

• 54,602.

Specification for Design.

Patented Mar. 9, 1920.

Application filed September 18, 1919. Serial No. 324,699. Term of patent 14 years.

To all whom it may concern:

Be it known that I, EDWARD P. COLE, a citizen of the United States, and a resident of Chicago, county of Cook, and State of Illinois, have invented a new, original, and ornamental Design for a Range-Top, of which the following is a specification, reference being had to the accompanying drawing, forming a part hereof.

The figure is a plan view of a range top showing my new design.

I claim:

The ornamental design for a range top, substantially as shown.

EDWARD P. COLE.
